UNITED STATES PATENT OFFICE.

WILLIAM P. PITTS, OF INDEPENDENCE, MISSOURI, ASSIGNOR TO IRVING-PITT MANUFACTURING COMPANY, OF KANSAS CITY, MISSOURI, A CORPORATION OF MISSOURI.

LOOSE-LEAF BINDER.

1,079,580.

Specification of Letters Patent.

Patented Nov. 25, 1913.

Application filed November 8, 1911. Serial No. 659,144.

To all whom it may concern:

Be it known that I, WILLIAM P. PITTS, a citizen of the United States, residing at Independence, in the county of Jackson and State of Missouri, have invented certain new and useful Improvements in Loose-Leaf Binders, of which the following is a specification.

My invention relates to improvements in loose leaf binders.

It relates particularly to loose leaf binders of the type having a follower slidably mounted on leaf supporting posts.

The object of my invention is to provide a structure which is cheap to manufacture, is durable, efficient in operation, and which is not liable to get out of order.

A further object of my invention is to provide a tubular follower in which the parts for clampingly engaging the leaf supporting posts are inclosed by the follower thus eliminating liability of accidental disarrangement of the operating parts and affording a compact structure which is attractive in appearance.

Other novel features of construction are hereinafter fully described and claimed.

While my invention is capable of embodiment in different forms, I have, in the accompanying drawings illustrated a preferred form of the invention.

Figure 1 is a vertical cross section of a loose leaf binder provided with my invention, the section being taken on the plane 35 of the line *a*—*b* of Fig. 2. Fig. 2 is a horizontal sectional view of the follower and posts, the binding being omitted, and the parts contained within the follower being shown in plan. Fig. 3 is a vertical sectional view on the plane of the line *c*—*d* of Fig. 2. Fig. 4 is a perspective view of the binder. Fig. 5 is an enlarged vertical sectional view of one of the clamping devices and parts connected therewith. Fig. 6 is a perspective 45 view of one of the clamping plates. Fig. 7 is a perspective view of one of the clamping blocks the spring mounted thereon and the roller wedge mounted therein. Fig. 8 is a perspective view of the slide bar for releasing the wedges.

Similar reference characters designate similar parts throughout the different views.

1 designates the base plate of the binder to which are secured one set of ends of two parallel leaf supporting posts 2.

A tubular follower, comprising preferably a tubular body 3 having end caps 4 provided with projections 5 which enter corresponding slots in the ends of the body 6. 3, is connected to a swinging cover 6 by ears 7 secured to one side edge of the body 3 and hinged to a pintle 8 mounted in a folded plate 9 secured to one end of the cover 6. The body 3 is provided in its upper and lower sides with holes 10 adapted to receive the posts 2. In the body 3 are located two clamping members comprising two plates 11 each having at its ends downwardly turned corner portions 12 which rest upon the bottom portion of the body 3. Each plate 11 is provided with a vertical hole 13 adapted to register with one set of holes 10 so as to receive the adjacent post 2. At one end of the hole 13 is provided a bearing portion 14 which is adapted to clamp against the adjacent post 2. At the other end of the hole 13 is an inclined seat 15 against which rests a wedge, preferably a roller 16, which is movable to and from a position in which it is adapted to engage the post 2 and force the post against the bearing portion 14.

For normally forcing the wedges 16 into locking engagement with the inclined seats 15 and posts 2, I preferably provide two springs comprising preferably spring plates 17 which are respectively mounted on the clamping members or plates 11 and are provided with holes 18 adapted to receive the posts 2 and tongues 19 which respectively bear upon the upper sides of the roller wedges 16 for forcing the rollers respectively downwardly against the seats 15. To retain each spring plate 17 in position on its supporting plate 11, it is preferably provided with downwardly extending corner projections 20 which rest upon the corner portions 12 of the plate 11. When the corner portions 12 are downwardly bent shoulders 21 are provided which serve to engage the projections 20 for preventing lengthwise movement of the spring plate on the plate 11. The upper sides of the spring plates 17 bear upon the under side of the upper part of the body 3, thereby causing

the spring plates 17 to be securely held in position without the use of other securing means.

Horizontally and longitudinally slideable 5 in the body 3 is a releasing member comprising preferably a plate 22 having two longitudinal slits 23 through which the posts 2 are adapted to respectively extend. The plate 22 is also provided with upwardly 10 extending cams 24 which, when the plate 22 is moved longitudinally to the proper position, simultaneously engage and lift the roller wedges 16 from the locking positions, shown in Figs. 1 and 2 to the release position 15 shown in Fig. 5. To reciprocate the plate 22 I preferably provide a button 25 provided with a shank 26 which extends through a slot 28 provided in the upper side of the body 3, and has its lower end provided with 20 an annular groove 29 in which is located the plate 22. The plate 22 is provided preferably with a longitudinal slot 30 in a raised central portion 31 of the plate 22. The slot 30 has a central enlargement 32 which is a 25 little smaller in diameter than the shank 26. The lower end of the shank 26 is preferably beveled so that the shank may be forced into the slot 30 to the position shown in Fig. 1. The relations of the parts are such 30 that the resiliency of the plate 22 will spring the plate into the groove 29, the long slot 30 being provided so that in forcing the shank 26 into locked relation to the plate 22, the metal will not be stretched to too 35 great an extent to permit its springing back into the groove 29.

In the operation of my invention, the follower is mounted on the posts 2 and slid downward thereon until it clamps the loose 40 leaves 33 which are adapted to be mounted on the posts 2. Any attempt to move the follower upwardly will be prevented by the wedges 16 bearing against the posts 2 and the seats 15 thus forcing the posts against 45 the bearing portions 14 and causing the posts to be tightly clamped. Any downward movement of the follower on the posts 2 will cause the roller wedges 16 to lift from the seats 15 against the pressure of the 50 spring tongues 19. To release the leaves 33, the button 25 is slid in the slot 28 in a direction such that the cams 24 of the plate 22 will pass under the roller wedges 16. The wedges will thus be lifted from the 55 seats 15, as shown in Fig. 5, so that the follower will be free to be slid upwardly on the posts 2.

In order that the clamping plates 11 may be adjusted toward and from each other, 60 within predetermined limits, these plates are slidably mounted in the body 1 between inwardly extending projections 34 disposed at opposite ends of the plates 11 in the body 3. Each pair of projections 34 are spaced 65 apart sufficiently to permit of a small

amount of longitudinal movement of the plate 11. By means of this construction absolute accuracy in securing of the posts 2 at certain distances apart need not be attained. The holes in the base 1 in which 70 are secured the posts 2, and the holes 10 in the body 3 may be located by gaging during the steps of manufacture, and different dies for punching plates in which the holes are located at different distances apart need not 75 be provided. If the distance between the posts 2 of a binder varies to a small extent from the proper distance, the plates 11, being longitudinally movable, will adjust 80 themselves to the posts.

I do not limit my invention to the structure described and shown, as modifications of my invention, within the scope of the appended claims, may be made without departing from its spirit.

Having thus described my invention, what I claim and desire to secure by Letters Patent, is:

1. In a loose leaf binder, a tubular follower having a hole for receiving a post and having a slot, a clamping member in the follower and having a hole registering with the hole in the follower for receiving the post, said member at one end of the hole having a bearing portion and having an inclined seat, a wedge movable to and from a position in which it is adapted to engage the seat and post for forcing the post against said bearing portion, a spring for forcing the wedge to said position, a releasing member in the follower for forcing the wedge from said position, and an operating member extending through the slot for actuating the releasing member.

2. In a loose leaf binder, a tubular follower having a hole for receiving a post and having a slot, a clamping member in the follower and having a hole registering with the hole in the follower for receiving the post, said member having at one end of the hole a bearing portion and having an inclined seat, a wedge movable to and from a position in which it is adapted to engage the seat and post for forcing the post against said bearing portion, a spring for normally moving the wedge to said position, and means including a device slidably mounted in the slot for moving the wedge from said position.

3. In a loose leaf binder, a tubular follower having a hole for receiving a post and having a slot, a clamping member in the follower and having a hole registering with the hole in the follower for receiving the post, said member having at one end of the hole 125 a bearing portion and having an inclined seat, a wedge movable to and from a position in which it is adapted to engage the seat and post for moving the post against the bearing portion, means for normally 130

forcing the wedge to said position, a releasing member slidably mounted in the follower for moving the wedge from said position, and an operating member extending 5 through and slidable in the slot for actuating the releasing member.

4. In a loose leaf binder, a tubular follower having a hole for receiving a post, a clamping member having a hole registering with the hole in the follower for receiving the post, said member having at one end of the hole a bearing portion and having an inclined seat, a wedge movable to and from a position in which it is adapted 10 to engage the seat and post for forcing the post against said bearing portion, a spring for normally moving the wedge toward said position, and a releasing member slidable in the follower for moving the wedge from said position.

5. In a loose leaf binder, a tubular follower having a hole for receiving a post and having a slot, a clamping member in the follower and having a hole registering 25 with the hole in the follower for receiving the post, said member having at one end of its hole a bearing portion and having an inclined seat, a wedge movable to and from a position in which it is adapted 30 to engage the seat and post for forcing the post against said bearing portion, a spring for normally moving the wedge toward said position, a releasing member slidably mounted in the follower for moving the wedge from said position, and an operating member extending through and slidable in said slot for actuating the releasing member.

6. In a loose leaf binder, a tubular follower having two holes adapted to respectively receive two parallel posts, two clamping means adjustable relatively to each other in said follower and respectively including two wedges movable to and from positions in which they are adapted to respectively engage 45 said posts, and means for simultaneously moving the wedges from said positions.

7. In a loose leaf binder, a follower having two holes for respectively receiving two parallel posts, two clamping means adjustable on said follower toward and from each other and including respectively two wedges movable toward and from positions in which they are adapted to respectively engage said posts, and means for simultaneously moving said wedges from said positions.

8. In a loose leaf binder, a follower having two holes for respectively receiving two parallel posts, two clamping means including respectively two clamping members adjustable on said follower toward and from each other and two wedges movable toward and from positions in which they are adapted to engage said posts respectively and said

clamping members, two springs for respectively moving the wedges toward said 65 positions, and means for simultaneously moving the wedges from said positions.

9. In a loose leaf binder, a tubular follower having two holes adapted to respectively receive two parallel posts and having a slot, two clamping members mounted in said follower and having each a bearing portion and an inclined seat, two wedges movable to and from positions in which they are adapted to respectively engage said seats 75 and said posts for respectively forcing the posts against said bearing portions, means for normally moving the wedges toward said positions, and means including a device movable in said slot for simultaneously moving the wedges from said positions.

10. In a loose leaf binder, a tubular follower having two holes adapted to respectively receive two parallel posts, two clamping members mounted in said follower and having each a bearing portion and an inclined seat, two wedges movable to and from positions in which they are adapted to respectively engage said seats and said posts for forcing the posts against said bearing 85 portions respectively, two springs for respectively moving said wedges toward said positions, and means adapted to operate simultaneously on the wedges for moving them from said positions.

11. In a loose leaf binder, a plate having a slot, and a button having a shank provided with an annular groove in which the plate is located, the width and length of the slot and diameter of the shank being such that 100 the shank may be sprung into the slot without spreading the plate beyond the limits of its resiliency.

12. In a loose leaf binder, a plate having a slot provided with a central enlarged portion, and a button having a shank provided with an annular groove, the diameter of the grooved portion of the shank being greater than the width of the slot at opposite sides of the enlarged portion, and the diameter 110 of the shank at opposite sides of the groove being greater than the diameter of the enlarged portion of the slot, the width and length of the slot, the resiliency of the plate and the diameters of the shank being such 115 that the shank may be forced into the central enlarged portion of the slot without expanding the plate beyond its limits of resiliency.

In testimony whereof I have signed my name to this specification in presence of two subscribing witnesses.

WILLIAM P. PITTS.
